Primary Examiner—Alan P. Douglas*Assistant Examiner*—Robert M. Spear*Attorney, Agent, or Firm*—Howson and Howson[57] **CLAIM**

The ornamental design for the combined bag closure and handle, as shown and described.

DESCRIPTION

FIG. 1 is a perspective view of a combined bag closure and handle according to the invention;

FIG. 2 is a front elevational view of a combined bag closure and handle, the rear elevational view being identical thereto;

FIG. 3 is a right side view of FIG. 2, the left side view being identical thereto;

FIG. 4 is a top plan view of FIG. 1; and,
 FIG. 5 is a bottom plan view of FIG. 1.

*FIG. 1**FIG. 2*

FIG. 3

FIG. 4

FIG. 5
